John W. Maupin.

ATTORNEY

UNITED STATES PATENT OFFICE.

JOHN C. NELSON, OF SEATTLE, WASHINGTON.

STATION INDICATOR.

Application filed May 28, 1923. Serial No. 641,949.

My invention relates to improvements in station indicators and the principal objects of the invention are to provide a station indicator of simple, economic, and durable construction whereby the names of streets or other stops may be successively displayed to the occupants of passenger vehicles entirely by automatic means. Other objects are to employ a square prismatic drive roll member which is caused to make one quarter turns at predetermined intervals by pneumatic force from the compressed air tank acting through a valve controlled by a solenoid which is energized by switch contact with the main trolley wire of said vehicle.

With the above and other objects in view which will appear as the description proceeds, the invention consists of the novel construction, adaptation, arrangement and combination of parts hereinafter described and claimed.

These objects are accomplished by devices illustrated in the accompanying drawings, wherein—

25 Figure 1 is a view in longitudinal vertical section of a trolley car showing the device mounted therein;

Fig. 2 is a view in transverse vertical section of the same;

30 Fig. 3 is a view in front elevation of the casing and contents with the door removed;

Fig. 4 is a view in transverse vertical section of the same taken substantially on a broken line 4, 4 of Fig. 3 and showing the 35 valve and solenoid together with a diagram of electric wiring;

Fig. 5 is a detail fragmentary view in vertical section of the cylinder, valve and associated parts;

40 Fig. 6 is a detail fragmentary view of the rack, gear and ratchet drive mechanism;

Fig. 7 is a detail view in front elevation of the trolley connections;

Fig. 8 is a view in side elevation of the 45 same; and

Fig. 9 is a detail fragmentary view in vertical section of the roll and showing the means whereby the edge binding is adapted to hold a display advertising card.

50 Referring to the drawings, throughout which like reference numerals designate like parts, the numeral 5 designates an ordinary trolley car having the usual compressed air tank 6 mounted under its flooring. A pipe

55 7 leads from said tank to a three-way valve 8. The arm 9 of said valve is pivotally con-

nected to a rod 10 of a solenoid 11. A shunt circuit 12 communicates between said solenoid and the contact end of a trolley pole 13. The ends of said circuit are respectively connected with positive and negative brushes 14 seated in an insulator member 15 secured to the axle of the trolley shive 16. Contact plates 17 are secured to and in contact with the trolley wire 18 usually at the street corners.

When the brushes 14 come in contact with the plates 17 a current will pass through and energize the solenoid 11. The arm 9 and rod 10 will be drawn down to the position shown in dotted lines in Fig. 4 of the drawings and the three-way valve 8 will consequently be turned to the position shown in dotted lines in Fig. 5. When said brushes pass free of said plates the current will cease and a spring 19 encircling the rod 10 will force the arm 9 upwardly carrying the three-way valve back to its normal position.

In its normal position the three-way valve 8 is open to the free air through the port 20 shown in Fig. 5. When said valve is given a one quarter turn said free air port is closed and the passageway through the pipe 7 is opened permitting the air pressure to pass upwardly from the tank 6 as will be understood. The upper end of said pipe enters a cylinder 21 mounted within a casing 22. A piston 23 is operatively mounted within said cylinder and a piston rod 24 extends through the top of said cylinder terminating in a toothed rack 25. A spring 26 within said cylinder is adapted to normally hold said piston on its seat in the bottom thereof when said three-way valve is open to the free air, and when air pressure is admitted said piston is forced upwardly against an annular shoulder 27 within said cylinder.

The rack 25 engages a gear wheel 28 revolvably mounted on a shaft 29 rotatively mounted in the sides of the casing 22. A spring pawl 30 is mounted on said gear and engages a ratchet wheel 31 fixedly secured to said shaft. A square prismatic drive roll member 32 is also fixedly mounted on said shaft and has pins 33 respectively adjacent its four corners on both end portions thereof. The four sides of said square roll member are normally parallel with the four sides of the casing 22 and it will be understood that each complete movement of the piston 23 upwardly against the shoulder 27 will

cause said roll member to be turned a one quarter revolution thus retaining its parallel relation with the sides of said casing.

Tension rollers 34 and 35 are mounted to turn loosely on shafts 36 and 37 which have their squared end portions mounted in square slots (not shown) provided in the sides of said casing to keep them from turning. Said rollers have opposing springs 38 and 39 respectively mounted therein with one of their ends fixed to said shaft and the other end fixed to a flange of said roller. Said two rollers are identical in all respects and may be interchanged or turned end for end in their bearings. Hooks 40 and 41 are respectively secured to the opposite ends of said rollers and are adapted to lock said rollers to said shafts and thus hold the tension caused by said springs.

20 A roll 42 of thin flexible fabric is arranged to be wound back and forth on the rollers 34 and 35 and passes over the drive roll member 32 as clearly shown in Fig. 4 of the drawings. Thin metallic bindings 43 are crimped, glued or otherwise fastened to the longitudinal edge portions of said roll. The inner edge portions of said bindings are deflected from said roll, as at 44 in Fig. 9, to permit the edges of cards 45, such as display advertisements, to be inserted therein and held transversely across said roll as will be understood. Holes 46 are provided through said bindings in spaced apart relation to engage the pins 33 when said drive roll is set in motion.

40 A door 47 is hingedly secured to the casing 22 and a window 48 is provided in said door opposite the drive roll member 32. Said casing is ordinarily mounted in the forward end of a trolley car over the front door in view of the passengers. The names of the successive streets or other stops are printed on the roll 42 in spaced apart relation to register with the upper portion of the window 48 at each quarter turn of said drive roll member. The advertising cards

45 are arranged for observation through the lower portion of said window immediately below the street names.

50 Referring to Fig. 3 it will be seen that sufficient space is provided within the casing 22 at the ends of the tension rollers 34 and 35 for entry of the hands in reversing, interchanging or otherwise manipulating said rollers. On loop or belt car lines the 55 roll 42 may be designed to carry the names of all the stops without reversing said roll. On other car lines the names of the return stops may be printed on the opposite side of said roll and same may be reversed at the 60 end of the line as hereinbefore indicated.

Having thus described my invention, it being understood that such changes may be made as are within its scope and spirit, what I claim and desire to secure by Letters 65 Patent is:—

A station indicator comprising a compressed air tank, a three-way valve normally open to free air, pipe connection between said tank and valve, a solenoid adapted to actuate said valve, spring means for said solenoid, a cylinder on the end of said pipe mounted within a casing, a door and window for said casing, a piston and rod within said cylinder, a spring for said piston, an annular shoulder within said cylinder, a rack on said rod, a square prismatic drive roll member having its sides parallel to said casing, pins on said drive member, gear means engaging said rack, ratchet means adapted to impart one quarter turn to said drive member, tension rollers, opposing springs for said tension rollers, a flexible roll on said tension rollers in engagement with said drive roll member, bindings on the edges of said flexible roll having holes therein arranged to engage said pins, an electric circuit for said solenoid, and contact means for said circuit comprising plates and brushes substantially as described.

JOHN C. NELSON.
